(57) CLAIM

The ornamental design for a quad stamp pad holder, as shown and described.

DESCRIPTION

FIG. 1 is a perspective view of a stamp pad holder embodying the present invention;

FIG. 2 is a front elevation thereof, with the left side, right side and rear elevation view being identical thereto;

FIG. 3 is a top plan view of the stamp pad holder; and, FIG. 4 is a bottom plan view thereof, wherein the broken lines are for illustrative purposes only and form no part of the claimed design.

1 Claim, 4 Drawing Sheets
